TOOL RACK

Rudolph J. Maro, 14307 Puritas Ave., Cleveland, Ohio

Filed July 12, 1957, Ser. No. 46,921

Term of patent 14 years

(Cl. D54—13)

Figure 1 is a front elevation of a tool rack, showing my design;

Figure 2 is a sectional view on a larger scale and taken along the line indicated at 2—2 in Fig. 1. A pegboard is shown in broken lines for illustrative purposes only.

Fig. 3 is a front elevational view of the tool rack of Fig. 1 except that the bottom ledge is on top to better illustrate the same.

I claim:

The ornamental design for a tool rack, as shown and described.
